(57) **CLAIM**

The ornamental design for a hat, as shown and described.

DESCRIPTION

FIG. 1 is a perspective view of a hat according to the present invention.

FIG. 2 is a left side elevational view of the hat shown in FIG. 1.

FIG. 3 is a right side view of the hat shown in FIGS. 1 and 2.

FIG. 4 is a top view of the hat shown in FIGS. 1-3.

FIG. 5 is a front view of the hat shown in FIGS. 1-4.

FIG. 6 is a rear view of the hat shown in FIGS. 1-5; and,

FIG. 7 is a bottom view of the hat shown in FIGS. 1-6.

The broken lines in the figures show portions of the hat which form no part of the claimed design.
